(57) **CLAIM**

The ornamental design for a wireless soil sensor, as shown and described.

DESCRIPTION

FIG. 1 is a perspective view of a wireless soil sensor of the present invention.

FIG. 2 is a first side view of the wireless soil sensor of FIG. 1.

FIG. 3 is an opposing side view of the wireless soil sensor of FIG. 1.

FIG. 4 is top plan view of the wireless soil sensor of FIG. 1.

FIG. 5 is a bottom plan view of a wireless soil sensor of FIG. 1; and,

FIG. 6 is a front view of the wireless soil sensor of FIG. 1.
